UNITED STATES PATENT OFFICE

HERMAN SWISSLER, OF CHICAGO, ILLINOIS, ASSIGNOR TO LOUIS BIEGLER COMPANY,
OF CHICAGO, ILLINOIS, A CORPORATION OF ILLINOIS

METAL WINDOW SASH AND THE LIKE

Application filed August 17, 1929, Serial No. 386,568. Renewed November 2, 1932.

This invention has to do with certain improvements in metal window sash and the like. The improvements concern themselves particularly with the arrangement of 5 seams whereby the sheet metal parts are secured together.

The main object of the invention is to provide a window sash having certain of the 10 seams by which the metal strips are locked together so formed and placed as to make it possible to materially reduce the vertical dimensions of certain of the horizontal rails of the upper and lower sash of the window. In other words these features of the invention 15 make it possible to materially reduce the amount of surface exposure of the horizontal rails in which the features of the invention are incorporated, with corresponding increase in the superficial area of the glass or opening of the window sash. The amount of this increase of area due to narrowing of the horizontal sash rails is a very 20 substantial percentage of the total and will in many cases amount to as much as 15-25 25 per cent increase in the glassed opening.

Another object of the invention is to provide an arrangement of seams such that a maximum of strength and rigidity of the metal frame is produced.

30 A further object of the invention is to provide an arrangement such that the seam is brought to one of the edges of the sash where it is least objectionable from the standpoint of visibility; and at the same time the bringing of the seam into this location makes it possible to finish it by cementing and painting under conditions which are most advantageous for the complete elimination of any objectionable 35 appearance due to the presence of the seam.

In order that the features of the invention may be better understood and their significance and relevancy may be appreciated, I will state that the ability to produce a 40 given seam within a given location depends not merely upon the form and size of the seam, but also depends upon its location and position with respect to other portions of the sheet metal structure. This is true because of the necessity of using dies and tools

for "breaking" or bending the metal along the desired lines, and these dies and tools require the presence of a sufficient amount of space to accommodate them and make it possible to manipulate them. For these 55 reasons a seam of a specified form and size may be produced with certain clearances with respect to other surfaces when located in one position, but may require greater 60 clearances when located in a different position with respect to the same surface.

In the drawings:

Figure 1 shows a vertical section through a two sash window, the central portions of the upper and lower sash and adjacent window casing structures being broken away to shorten the figure. The upper rail of the lower sash and the upper and lower rails of the upper sash are provided with seams embodying the features of the present invention;

Figure 2 shows a fragmentary detailed section through the upper railing of the lower sash and the lower railing of the upper sash of Figure 1 on enlarged scale;

Figure 3 shows a detailed section through the lower rail of the lower sash of Figure 1, on enlarged scale;

Figure 4 shows a horizontal section taken substantially on the line 4-4 of Figure 1, looking in the direction of the arrows and it also shows a vertical muntin bar in the central portion of the upper sash;

Figure 5 shows a fragmentary face view of the upper corner of one of the sash showing how the stile and cross rail are riveted together in the corner; and

Figure 6 shows a fragmentary section through the upper rail of the lower sash and the lower rail of an upper sash of a previous type of construction in which the seam is located on the horizontal surface of the rail instead of on its vertical surface so that it is impossible to procure the advantages and benefits of the reduction of size 90 of rail which can be secured in the case of the present invention.

In the several figures I have illustrated the lower and upper sash 7 and 8 respectively. These are mounted in a suitable win-

dow case including the sides 9 and 10, the sill 11 and the top 12.

Considering the bottom sash 7, the same includes the stiles 13 and 14, the top cross rail 15, and the bottom cross rail 16. Each of the stiles includes a sheet bent to establish the ogees 17 and 18 which are joined together at their inner edges by the U-shaped or grooved portion 19, which receives the edge of the glass panel 20. The edges of the sheet are then carried outwardly in the flanges 21 and 22 and are reentered or turned backwardly on themselves as shown at 23 and 24 to establish inwardly facing grooves. Another channel shaped sheet 25 has its edge portions turned outwardly and properly spaced and of proper depth to work in the channels 23 and 24. Consequently, when the flanges of the sheet 25 are slid into the groove portions 23 and 24, the two sections are effectively locked together into a hollow stile. Said edge portions may be soldered or riveted or otherwise secured if necessary.

25 The bottom cross rail 16 is established by a sheet which is so folded as to provide the ogees 26 and 27 which are joined along their inner edges to establish a channel 28 to receive the lower edge of the glass pane 20. 30 One edge of this sheet is then carried down and is refolded on itself to establish a double thickness lip 29 along the inner lower edge of the rail, and such refolded portion is again refolded along its upper edge as shown at 30 to establish an outwardly facing channel. A similar construction is employed at the outside face of the lower rail 16 to establish the tongue 31 of double thickness, the upper edge portion of which is 35 refolded as shown at 32 to establish an outwardly facing locking groove. A plate 33 has its edges folded backwardly on themselves to correspond to the grooves 30 and 32 so that said plate 33 may be slid into 40 place as shown in Figure 1 in order to complete the construction of the lower rail 16. Said plate 33 may also be soldered or riveted in place if necessary.

45 The top cross rail 15 is established by a sheet which is so folded as to provide inner and outer ogees 34 and 35 respectively between which there is established the channel portion 36 to receive the upper edge of the glass pane. The ogee 35 is carried out and then the sheet is turned upwardly as shown at 37 and is refolded downwardly as shown at 38 to establish a downwardly facing channel, the position of which is directly opposite to the upper portion of the channel 36.

Beyond the position of the other ogee 34 the sheet is carried upwardly as shown at 39 and then outwardly and downwardly as shown at 40 to establish a downwardly facing channel which is located directly oppo-

site to the upper portion of the channel 36.

A top plate 41 has its inner edge reversely folded as shown at 42 and then carried downwardly and folded upwardly as shown at 43 so as to establish a locking groove and tongue portion which directly engages the portion 38 of the other sheet. The other edge of the sheet 41 is turned downwardly and then upwardly on a reverse fold as shown at 43 to establish an upwardly facing channel to engage the edge portion 40 already referred to.

70 The sheet 41 is slipped into place lengthwise with respect to the cross rail 15 and is simultaneously locked into the edge portions of the ogee shaped sheet; and if desired the two sheets may be soldered or riveted or otherwise secured together as necessary.

75 It will be noted that the flat portion of the sheet 41 may be laid directly against the top edge of the channel 36 as best shown in the detail of Figure 2. The channel 36 thus constitutes the limiting factor which determines the position of the sheet 41 in the sense that said sheet can not be set any 80 lower down without making the channel 36 correspondingly shallower. Thus for a given depth of channel 36 the sheet 41 is at its lowest position when in contact with the channel.

85 The locking grooves 43 and 38 are formed in a vertical direction and parallel to the plane of the glass pane 20. This brings the exposed joint or seal 44 along the corner or edge of the sash instead of along one of its faces. In such location said joint may be most easily and conveniently sealed by soldering or otherwise; and when so sealed the structure presents a practically perfect and continuous surface across the entire 90 joint. Even when this joint is not sealed by soldering throughout its length, it is of such small and unobtrusive nature that the paint will itself practically seal the joint and establish the continuity of the surfaces. 95

100 At this point I wish to make reference to the construction shown in Figure 6 by way of comparison. The arrangement shown in Fig. 6 is substantially similar to that so far 105 described with respect to my improved horizontal or cross rail 15 with the exception that the top plate 41^a in Figure 6 is located a considerable distance above the channel 36^a so that the vertical dimension of the cross rail 15^a is correspondingly increased. Furthermore, in the construction of Figure 6, the sheet metal plate is carried out beyond the position of the ogee 35^a and then upwardly and is then turned into a horizontal 110 position before forming the channel 38^a. Likewise, the edge of the plate 41^a does not have to be turned downwardly as shown at 42 in Figure 2; but on the contrary the channel 43^a is placed in a horizontal direc- 115 120 125 130

tion so as to engage the channel 38^a in the manner indicated in Figure 6.

The differences of structure as between the arrangement shown in Figure 6 and the arrangement shown in the other figures is important and of a very definite nature as the following explanation will show;

In order to form the channel 38^a in the structure of Figure 6, which channel lies in a horizontal plane and above the upper edge of the channel 36^a, it is necessary to have a sufficient clearance between the inner edge of said channel 38^a and the top edge of the channel 36^a to make possible the use of a die 15 of sufficient strength to do the work. This clearance can not possibly be established in the case of cross rails for window sash of the type shown in Fig. 6 except by raising the channel 38^a a substantial distance above the elevation of the channel 36^a and with corresponding increase in the vertical overall dimension of the cross rail 15.

On the contrary in the type of construction to which this invention relates and as shown especially in the detail of Figs. 1 and 2, the necessary clearances can be established between the channels 38 and 36 to accommodate dies of sufficient mechanical strength to do the work even when the channel 38 is set down to a low position and opposite to the channel 36 as shown in Figure 2 in particular. The reason for the above condition is readily apparent since the depth of the channel 38 or 38^a is necessarily very much greater in amount than the thickness of said channel or the clearance between the folds of the sheet.

Because of the above condition I am enabled by placing the channel 38 on the vertical fold of the metal instead of on the horizontal fold thereof, to very materially reduce the vertical dimension of the cross rail and lower the plate 41 down to the position of the channel 36 which then becomes the limiting factor.

If desired a lock plate 45 may be set between the channel 36 and the fold 39 (see Fig. 2) and said lock plate is covered over by the sheet 41 when in place. The window lock is then screwed or otherwise connected to the lock plate 45.

In like manner a handle plate 46 may be set into the lower cross rail to receive the lifting handles which are screwed or otherwise attached to it.

The adjoining ends of the stiles and cross rails are preferably riveted or soldered together in order to join them securely and also for the purpose of providing the necessary rigidity in the sash itself. For this purpose the facing plate sections of the end portions of the stiles and cross rails are lapped as shown in Figure 5 and are then joined by rivets such as 47. In connection with the foregoing it will be understood that

the metal ordinarily used in building these sash is relatively thin as for example approximately $\frac{3}{2}$ of an inch thick, so that the slight shoulder established at this point of overlap is not seriously objectionable. The paint will serve to largely eliminate or efface such shoulder and give a smooth finished surface.

It is customary in the case of metal frame window sash to divide the glass into two or more panes or sections, the adjoining edges of which are connected together and supported by what are known as muntin bars. Such a muntin bar is shown at 48 in Figure

4. It comprises the inner and outer sections of suitable construction which are connected and secured together by screws 49 after the glass panes have been set into place. In setting the glass panes into place it is usually necessary to make provision in the top cross rail of the sash to allow the pane to be raised far enough so that its lower edge can then be set over and dropped down into the groove of the lower rail. This makes it necessary to provide the extra depth of the channel 36 shown in Figures 1 and 2; but in any case the plate 41 may be set down against the top of this channel by using the features of the present invention.

The glass panes are puttied or otherwise cemented into place in the customary manner.

The upper sash 8 is of construction similar in many respects to that already described in detail with respect to the sash 7; and the features of invention of the joints may be used in the case of the sash 8. Thus for example, the joints 50 and 51 for the upper cross rail 52 and the joint 53 for the lower cross rail 54 may be formed in the same manner as the joint at 38 for the upper cross rail 15 already described. I wish to emphasize the fact that the ability to place the cap plate such as 41 in substantial contact with the channel 36 results in a very material reduction of the vertical dimension of the cross rail so that the corresponding increase in the area of the exposed glass is produced, which in practice actually amounts in many cases to fifteen per cent or more of such glass area.

While I have herein shown and described only a single embodiment of the features of my present invention, still I do not intend to limit myself thereto except as I may do so in the claim.

I claim:

A window sash including a horizontal cross rail formed from a pair of sheet metal sections, one of said sheet metal sections being folded to establish a central vertical pane receiving channel and being formed with ogee sections at the sides of said channel and being continuous across said channel, a flange projecting outwardly from the
